UNITED STATES PATENT OFFICE

164,849

TRAFFIC LIGHT INDICATOR

Hans G. Faltin, York, Pa.

Application August 3, 1951, Serial No. 16,139

Term of patent 14 years

(Cl. D72—1)

To all whom it may concern:

Be it known that I, Hans G. Faltin, a citizen of the United States of America, residing at York, in the county of York and Commonwealth of Pennsylvania, have invented a new, original, and ornamental Design for a Traffic Light Indicator, of which the following is a specification, reference being had to the accompanying drawing, forming a part thereof, in which

Fig. 1 is a perspective view of a traffic light indicator embodying my new design;

Fig. 2 is an end elevational view;

Fig. 3 is a side elevational view;

Fig. 4 is a transverse cross-sectional view, taken on the line 4—4 of Fig. 3; and

Fig. 5 is a longitudinal cross-sectional view, taken on the line 5—5 of Fig. 2.

I claim:

The ornamental design for a traffic light indicator, as shown.

HANS G. FALTIN.
